United States Patent Office

Des. 195,735
Patented July 23, 1963

195,735

DRILL PRESS

Rutherford B. Snyder, Jr., Bradford Woods, Pa., assignor
to Rockwell Manufacturing Company, Pittsburgh, Pa.,
a corporation of Pennsylvania

Filed Oct. 17, 1962, Ser. No. 72,160

Term of patent 14 years

(CL D54—14)

Des. 195,735

PAGE 2

Fig. 3

Fig. 4

FIGURE 1 is a front elevation of a drill press embodying my new design;

FIGURE 2 is a right-hand elevation of the drill press of FIGURE 1;

FIGURE 3 is a rear elevation of the drill press of FIGURE 1;

FIGURE 4 is a left-hand elevation of the drill press of FIGURE 1;

FIGURE 5 is a top plan view of the drill press of FIGURE 1; and

FIGURE 6 is a section through the upper end of the drill press of FIGURE 1, taken substantially along line 6—6 of FIGURE 5.

The top of the work table and base are substantially flat and planar.

I claim:

The ornamental design for a drill press, substantially as shown and described.
